PACKAGING MACHINES

Adolph S. Dorosz, Beverly, and Armand L. Tardiff, Salem, Mass., assignors to United Shoe Machinery Corporation, Boston, Mass., a corporation of New Jersey
Filed Oct. 29, 1965, Ser. No. 505,710
6 Claims. (Cl. 53—377)

This invention relates to packaging machines and more particularly is directed to apparatus for folding blanks during the formation of display packages.

There is shown in U.S. Patent No. 3,195,284, one form of machine for making display packages. As shown in said patent the package produced therein and which also may be contemplated by the present invention is formed from a flat blank comprising a supporting frame of relatively rigid material having a window opening covered by a sheet of heat formable transparent plastic material. The plastic window is shaped to receive an article, the blank being folded after the article is placed.

Such packages have found wide acceptance and in order to extend their use, it is essential that machinery used in their production be capable of high speed and increased output over machines presently in use. One problem encountered is increased speed as well as simultaneous multiple production of the package involves the precise control of the package blanks while being folded. Accordingly, it is an object of the present invention to overcome the problems encountered with increased speed and precise control of the folding operation. To this end the machine is provided with a folding station on the feed path of the package blanks. At this station folding arms are provided which are initially adjacent but out of the feed path of the blanks. The blanks are intermittently fed and located so the leading ends are engageable by the arms. The arms are swung through the feed path so as to fold the blank at a predetermined fold line while the blank is held fixed by suction cups. While the blank is held folded by the arms, a pair of feed grippers close on the folded blank to maintain the fold. Thereafter, the arms and the suction cups are retracted and the grippers advance the folded blank to a fixing station where the folded blank is secured together. A pair of fixed grippers between the folded and fixing stations hold the folded card in the interval while the feed grippers release the blank and the fixing station secures the folded blank together.

The above and other features of the invention together with novel details of construction and combination of parts will now be described with particular reference to the drawings and thereafter will be pointed out in the claims.

In the drawings,

FIG. 1 is a side elevation of a typical packaging machine in which the invention may be embodied;

FIG. 2 is a perspective view showing a portion of the machine particularly at the blank folding station;

FIG. 3 is a plan view with parts broken away showing the feed drive mechanism;

FIG. 4 is a section on line IV—IV of FIG. 3;

FIG. 5 is a side elevation with parts broken away of FIG. 4;

FIG. 6 is a section substantially similar to that shown in FIG. 4 but illustrating the drive mechanism for the fixed gripper;

FIG. 7 is a view partly in section of control mechanism adjacent the mechanism of FIG. 6;

FIG. 8 is a section substantially on line VIII—VIII of FIG. 3;

FIG. 9 is a side elevation with parts broken away to illustrate the blank folding mechanism;

FIG. 10 is a view similar to FIG. 9 and illustrating the positions of the various parts during blank folding; and

2

FIG. 11 is a plan view of the mechanism shown in FIG. 10.

A typical machine in which may be embodied the folding apparatus of the present invention is shown in FIG. 1. The machine at one end is provided with a blank feeding mechanism A adapted to deposit blanks individually on guideways 2 (FIG. 2) and rails 4 which extend through the machine to guide each blank along a predetermined path. The path extends through a film heating station B, a pocket forming station C, product loading stations D, a folding station E, a sealing or fixing station F and a film shrinking station G. The only station that will be described in detail as pertinent to the present invention is the folding station E. It should be understood that the entire machine shown is merely a typical example of one machine in which the present invention may be used.

After the blank is placed on the guideways 2 and rails 4 a plurality of pairs of reciprocating feed grippers 6 (only one pair of which is shown in FIG. 2) grip each blank in succession and feed it successively to a plurality of pairs of fixed grippers. The fixed grippers are open while the blanks are advanced and are closed to hold and precisely locate the blank at each station while the feed grippers are opened and returned to feed the next blank. In this manner each blank is kept under precise control while it is fed to each station. Referring particularly to FIGS. 4 and 5, the operation and construction of the feed grippers and the fixed grippers will now be described. Each feed gripper 6 comprises a movable jaw 8 and an anvil jaw 10. The anvil jaws 10 are elongated and connected together throughout the length of the machine to form the guideways 2. The jaws 10 are carried by brackets 12 secured to two long feed bars 14 which extend along the length of and at opposite sides of the machine. The feed bars are guided for reciprocating movement in guides 16 mounted on portions of the machine frame 18. Each movable jaw 8 is pivoted on a pin 20 in each bracket 12 and is provided with an arm 22 connected to the piston rod 24 of a fluid operated cylinder 26 carried on pivots 28 in the bracket. Introduction of pressure fluid to the cylinder acts to close the jaw 8 to clamp a blank 30 against the jaw 10.

The bars 14 are reciprocated in unison by means of the mechanism shown in FIGS. 3 and 8. Each bar is provided with a depending lug 32 (FIG. 8), the lower end of which is received in a slot 34 (FIG. 3) in a bracket 36. The bracket is provided with bearings 38 adapted to slide on a rod 40 fixed at opposite ends in cross bars 42 of the machine frame. At one end the bracket is guided in a groove 44 in a bar 46 also secured to the machine frame. For reciprocating the bracket and hence also the bars 14 and feed grippers, a slot 48 in the bracket receives a pin 50 upstanding from a lever 52. The lever is pivoted at 54 and is provided with a sprocket 56 carrying a chain 58 which runs over idler sprockets 60 and is secured at opposite ends to members 62, 62 connected by a plate 64. The plate 64 has headed pins 66 running in slots 67 in support members 68 secured to the machine frame. The members 62 are connected to the opposite ends of piston rods 70, 71 extending from a fluid operated drive cylinder 72, and a speed control cylinder 73, respectively, the cylinders being secured to the undersides of the members 68. As shown in FIG. 3, the various parts are in their initial positions prior to initiation of a blank feed cycle. By introducing pressure fluid to the left end of cylinder 72, the chain 58 is driven to the right causing counterclockwise swinging of lever 52. Through pin 50, this movement also drives the bracket 36 and bars 14 and feed grippers 6 also to the right until lever 52 engages an adjustable stop screw 76. For controlling the rate of blank feeding movement of the feed grippers the fluid in the right end of cylinder 73 is driven out of the cylinder

at a rate determined by an adjustable flow control valve (not shown). Thus it may be seen that by varying the flow rate of fluid exhausted from cylinder 73, the feeding speed of the feed grippers may be infinitely varied.

At the end of the feeding stroke of lever 52, an adjustable screw 77 actuates a switch 78 to signal to the various stations that the feeding of blanks has terminated and operations to be performed on the blanks also can be commenced. At this time a signal also is given to cause a plurality of pairs of fixed grippers 80 (which are open during the feed movement as seen in FIG. 4) to clamp the opposite edges of the blanks 30 against members 82 secured to the frame 18 (see also FIG. 2). To this end the grippers 80 are mounted for limited rotation on two shafts 84 extending along opposite sides of the machine as seen in FIG. 8. The rotation of the grippers on shaft 84 is limited by keys 86 fixed in the shafts and extending into arcuate slots 88 in the grippers. As seen in FIG. 5, a torsion spring 90 on the shaft has one end fixed in the gripper 80 and the other end fixed in a collar 91 secured by a set screw on the shaft. A sleeve 92 provides a cover for the spring and together with a collar 93 fixed on the shaft locates the gripper 80 endwise on the shaft. The shaft 84 also has fixed thereto an arm 94 (FIG. 6) connected to the end of a piston rod 95 extending from a double acting fluid operated cylinder 96 pivoted at its lower end to a part of the machine frame. Operation of the cylinder in one direction on signal from switch 78 causes clockwise rotation of the shaft 84. Through spring 90 the grippers 80 are also swung clockwise to clamp the blanks against movement while the feed grippers 6 are opened and returned and the various stations perform their operation on the blank. The rotation of shaft 84 closing grippers 80 causes a lobe 81 (FIG. 7) on cam 83 fixed on the shaft to actuate a switch 85 to signal that the feed grippers may be opened. Thus, it may be seen that the feed movements of the blanks and their location at the various stations are precisely controlled at all times by the feed grippers and the fixed grippers without opportunity for the blanks to be misplaced.

Referring particularly to FIGS. 2 and 8 through 11, the blank folding station E will now be described. As above stated, each blank 30 is fed by the feed grippers 6 intermittently through stations B to D with fixed grippers 80 precisely locating each blank while being operated upon. The blanks are fed from station D and into the folding station E where the blank is to be folded to enclose an article in the film pocket of the blank. At this station, no fixed grippers are provided to hold the blank since they would interfere with the folding operation. Thus, to hold the blank positioned as well as to assist in the folding operation suction cups 100 (FIGS. 9-11) are provided to grip the underside of the blank adjacent its fold line. Each cup is mounted on the upper end of a piston rod 102 extending from a cylinder 104 secured to the underside of rails 4. While the blank is being fed into station E the suction cups 100 are held retracted by cylinder 104 below the path of movement of the blank as seen in FIG. 9. When the blank 30 has been positioned by the feed grippers at the end of their feed stroke, pressure fluid is introduced to cylinder 104 to raise cup 100 into engagement with the underside of the blank as seen in FIG. 10. At this time a source of vacuum (not shown) is applied to the cup through a passage 106 in the piston rod 102 so the blank is firmly gripped by the cup adjacent the fold line of the blank. As soon as the cups have gripped the blank the feed grippers may be opened to release the blank and to avoid interference with the folding operation. To ensure that the blank is folded on a predetermined line where the blank is usually scored, the ends of fingers 108 arranged above the blank terminate at the fold line. The fingers are carried by brackets 110 adjustably secured to bars 112 fixed to a rod 114 also fixed in members 116 upstanding from the machine frame. To ensure that the blanks are maintained

in the predetermined feed path as they are fed from station to station the bars 112 also carry one end of flexible strips 118 which overlie the blank between the windowed areas. For folding the blanks, arms 120 are pivoted under rails 4 at 122 and are connected by links 124 to levers 126. The levers 126 are fixed on a hexagonal shaft 128 which also carries an arm 130 connected to a piston rod 132 of a cylinder 134 pivoted at 136 to the machine frame. Initially, the folding arms 120 are in the positions shown in FIG. 9 below the feed path of the blanks. The leading end of each blank is fed by the feed grippers into position to be subsequently engaged by the arms 120 and the fold line is positioned at the ends of fingers 108. As soon as the suction cups 100 grip the blank and the feed grippers are opened, pressure fluid is introduced into cylinder 134 and through arm 130 and levers 126, the folding arms 120 are swung upward through the feed path to fold the leading end of the blank upward and over the trailing end to the position seen in FIG. 10. At this time, the feed grippers have been returned and the next pair of feed grippers are located adjacent the blank fold line. This next set of feed grippers are closed on the folded blank and a reversal of pressure fluid in cylinder 134 causes the folding arms 120 to be retracted to their initial positions out of the feed path of the blanks and causes the vacuum in cups 100 to be relieved and the cups to be retracted to their initial positions. At the end of the retraction movements, arm 130 actuates a switch 140 to signal the end of the folding operation and to commence the next feed stroke of grippers 6. The folded blank then is fed from the folding station E to the fixing station F. At the end of the feed stroke the folded blank is located in station F and grippers 80 (FIG. 2) at this station clamp the folded blank in accurate location while the blank is secured together and the feed grippers are opened and returned to initial position at the folding station in preparation for gripping and feeding the next folded blank.

From the foregoing it may be seen that each blank 40 is fed along a feed path well defined by guideways 2, rails 4, strips 118 and fingers 108. From the time that each blank is placed in this path at the station A, the blank is at all times accurately controlled either by the feed grippers 6 or the fixed grippers 80. With such precise control the blanks may be fed at high speed with assurance of accurate location at each station. Obviously, certain substitution of mechanisms and stations can be utilized without departing from the scope of the invention.

Having thus described our invention, what we claim as new and desire to secure by Letters Patent of the United States is:

1. In a machine for making packages from foldable blanks moved along a predetermined path, a folding station on said path and having at least one folding arm initially located adjacent said path, means for feeding each blank along said path to a position where one end is engageable by said arm, means for swinging said arm from its initial location through said path for folding said one end over the other end of the blank, a pair of reciprocating feed grippers, means for closing said grippers on the blank held folded by said arm to hold the blank folded while the arm is returned to its initial location, and means for moving said closed grippers for advancing the folded blank from said folding station to a station for fixing the folded blank together.

2. In a machine according to claim 1, in which the feed grippers are open and are positioned adjacent the fold line of the blank while the blank is folded by said arm.

3. In a machine according to claim 1, in which fixed grippers are provided between the folding station and the fixing station, said fixed grippers being open while the blank is fed by the feed grippers and being closed to hold the blank folded and in fixed position while the feed grippers are opened and returned to their initial position.

4. In a machine according to claim 1, in which at least one suction cup is provided at the folding station for gripping the blank adjacent its fold line while the blank is being folded by said arm.

5. In a machine according to claim 4, in which means are provided to engage said cup with the blank for gripping during the folding operation and to retract said cup for releasing the blank after the folding operation.

6. In a machine according to claim 1, in which at least

one finger is provided over which the leading end of the blank is folded by the folding arm.
